UNITED STATES PATENT OFFICE.

JOHN ASTROM, OF FORT WAYNE, INDIANA, ASSIGNOR TO FORT WAYNE ENGINEERING
& MANUFACTURING CO., OF FORT WAYNE, INDIANA.

PUMP.

1,328,474.

Specification of Letters Patent. Patented Jan. 20, 1920.

Application filed November 11, 1919. Serial No. 337,274.

To all whom it may concern:

Be it known that I, JOHN ASTROM, citizen of the United States, and resident of Fort Wayne, in the county of Allen and 5 State of Indiana, have invented certain new and useful Improvements in Pumps; and I do hereby declare that the following is a full, clear, and exact description thereof.

My invention relates to new and useful 10 improvements in pumps, more particularly of that relatively small type shown in my previous Patent No. 1,196,920, issued Sept. 5, 1916, and adapted for use in connection with domestic water distributing systems, or 15 for other uses where it is desirous to provide a compact pump unit.

It is in general the object of my invention to simplify and otherwise improve the structure and to increase the efficiency of 20 pumps of this character and also to increase their durability under the average conditions of use.

Pumps of this character have been heretofore constructed with an open well between 25 the crank casing and engine cylinder, to receive a packing box which surrounds the piston rod. Under the unskilled manipulation of the average user of this type of pump the stuffing boxes have been frequently tightened to an excessive degree, 30 thus setting up adverse conditions of operation.

It is therefore a more specific object of my invention to provide an arrangement where- 35 in the packing structure of the piston plunger is rendered fairly foolproof against careless adjustment and wherein the piston plunger may be completely inclosed to thus prevent the introduction into its bearings of 40 dust and other foreign matter which might otherwise settle thereon.

A further object is to provide an integral body casting for the pump which facilitates the complete inclosure of the piston plunger, 45 while at the same time preventing introduction of fluid from the crank casing into the pump cylinder or vice versa.

With the above and other objects and advantages in view, which will be apparent as 50 the description proceeds, my invention resides in the novel features of construction, combination and arrangement of the parts as hereinafter described and defined by the appended claims.

In the accompanying drawing:

The figure shows a vertical longitudinal 55 sectional view through a pump constructed in accordance with my invention.

Referring now more particularly to the accompanying drawing, it is noted that the 60 crank casing 5, cross head guideway 6, and pump cylinder 7 of the pump structure are formed in a single casting, together with a base frame portion 8. The crank casing 5 is of the usual circular shape and the cross 65 head guideway opens thereinto for the reception of the usual pitman 9 connecting the crank drive shaft 10 with the cross head member 11 which carries the usual crank pin 12. The guideway 6 is in axial alinement 70 with the pump cylinder and is closed at its end adjacent the pump cylinder by a wall 13 through which the piston plunger 14 is 75 slideable for connection with the cross head member. An annular chamber 15, surrounding the piston plunger is provided between the wall 13 and the inner end of the pump cylinder, this chamber being of greater diameter than the pump chamber, which it will be noted is formed by a lining sleeve 16 80 within the pump cylinder.

A suitable valve arrangement is provided at the outer end of the pump cylinder, preferably of the type shown in my said previous patent and including a head member 17 85 secured to a casing portion 18 surrounding the outer end of the pump cylinder, said head member being provided with an intake passage for a puppet valve 19, and having its end spaced from the end of the pump 90 cylinder to form a valve seat in co-operation with the end of the pump cylinder for the reception of a contractile valve ring 20. The usual air domes 21 are provided for the casing portion 18, which has a suitable outlet 95 (not shown) and for the inlet head member 17. The piston plunger 14 is provided with a reduced end portion within the pump chamber and this end portion is further reduced at its free extremity to provide a 100 shoulder 23 adapted to seat the base of a cup shaped packing member 24 having its annular wall extended into the space between the reduced plunger portion 22 and the periphery of the pump chamber. A bolt screw 105 25 is threaded in the plunger end and mounted on the screw bolt is a sleeve 26 having its end portion adjacent the packing

24 reduced for the reception of the base portion
25 of a second cup-shaped packing member
26 which has its annular wall directed forwardly with respect to the effective stroke
27 of the plunger and disposed between the sleeve 26 and the periphery of the pump
28 chamber. The forward end of the sleeve 26
29 is enlarged to substantially the diameter of
30 the pump chamber and is adapted to seat
31 the base portion of a third cup-shaped pack-
32 ing member 28 which has its annular wall
33 portion also forwardly directed, this pack-
34 ing member being secured against the sleeve
35 26 by a second follower sleeve 29 which has
36 its rear end portion reduced to form a shoul-
37 der and which has its forward end portion
38 increased in diameter to the diameter of the
39 pump chamber to provide a piston end sur-
40 face, the head of the bolt 25 being counter-
41 sunk in this surface.

I thus provide a pair of packing mem-
bers expansive against the wall of the piston
chamber to resist passage of water along
the piston plunger, and a rearward single
packing member to prevent leakage of air
into the piston chamber in reverse stroke of
the plunger, a positive packing action be-
ing thus procured without the necessity of
providing a packing gland at the end of the
pump cylinder. By providing the various
recited shoulder reductions of the ends of
the packing clamping members, I procure
a positive metal to metal mutual contact of
said members, upon tightening the screw
25, thus procuring an exceedingly efficient
and readily assembled packing structure
which does not depend upon any particular
degree of adjustment to procure its effi-
ciency, the clamping shoulders being so
spaced from the extremities of their respec-
tive members as to exert a proper action on
the interposed packing when the extremities
of the members are in abutting relation.

I thus provide an exceedingly simple and
highly efficient structure wherein the tend-
ency to tamper with the working parts of
the pump is eliminated by the complete in-
closure of said working parts, and inasmuch
as the piston plunger 14 is entirely inclosed
a considerable element of wear is avoided
inasmuch as said plunger is not exposed to
external conditions. By forming the entire
body structure of the pump in a single casting,
I procure a decided economy of struc-
ture and also eliminate the occurrence of
any joints or seams whatever between the
crank casing and the outer end of the piston
cylinder. The intermediate chamber 15 is
thus inclosed by integrally connected bound-
ing portions. The piston plunger working
through this chamber would shed into the
chamber any excess oil or any water which
might possibly find its way through the
packing and the chamber is provided with

a depending drain 30 extending through the
base portion 8 of the casting. I thus, de-
spite my entirely inclosed structure, posi-
tively avoid the possibility of oil finding its
way into the pump chamber, or of water
finding its way into the casing.

While I have shown and described a pre-
ferred embodiment of my invention, it will
be appreciated that various changes and
modifications of structure may be employed
to meet differing conditions of use and
manufacture, without departing in any man-
ner from the spirit of my invention.

What is claimed is:

1. A pump structure comprising a crank
casing, an inclosed cross-head guideway
and a pump cylinder all formed in a single
casting, valve mechanism at the outer end
of the cylinder, a cross-head in said guide-
way, a crank in the crank casing connected
with said cross-head, a piston plunger con-
nected with the cross-head and extending
into the pump cylinder, packing on said
plunger in the pump cylinder, and an an-
nular inclosed chamber surrounding the
piston plunger between the cross-head 90
guideway and pump cylinder.

2. In a pump structure of the class de-
scribed, the combination of a substantially
cylindrical cross-head guideway, a pump
cylinder formed in a single casting with
said guideway, a cross-head in said guide-
way, a piston plunger connected with said
cross-head and extending into the pump
cylinder, packing on said plunger in the
pump cylinder, and an annular chamber 100
surrounding the piston plunger between the
said guideway and the cylinder, said cham-
ber being bounded and completely inclosed
by integral connecting portions of the guide-
way and pump section.

3. In a pump structure of the class de-
scribed, the combination of a substantially
cylindrical cross-head guideway, a pump
cylinder formed in a single casting with
said guideway, a wall closing the end of the
guideway adjacent the pump cylinder and
provided with a bearing opening, said wall
being spaced from the end of the pump
chamber, a piston plunger connected with
the cross-head and slidabie in the bearing 110
opening of the said wall and extending into
the pump cylinder, packing on said plunger
in the pump cylinder, integral connecting
portions of the pump cylinder and guide-
way extending between the said wall and 115
the adjacent end of the pump cylinder to
define therewith an annular inclosed cham-
ber surrounding the piston plunger.

In testimony that I claim the foregoing
I have hereunto set my hand at Fort Wayne, 125
in the county of Allen and State of Indiana.

JOHN ASTROM.
